W. Va., a corporation of Delaware

Application May 27, 1943, Serial No. 488,663

10 Claims.

(Cl. 113—52)

This invention relates to spinning mechanism in which rotating work is shaped by a spinning roll. In spinning the work is first heated and then mounted for rotation and rotated rapidly, and during rotation of the work a spinning roll is brought into engagement with the work and pressed thereagainst to shape the work. Various hollow metal articles are formed by spinning, an example being bomb casings which are formed from metal tubes cut into lengths, the tube ends being spun inwardly until they are closed or partially closed.

Spinning machines have become fairly well standardized so far as the characteristic movements of the spinning roll relatively to the work are concerned. The spinning roll is customarily mounted on a carriage movable toward and from the work, such carriage being in turn carried by an arm, the arm being mounted on and pivotally movable relatively to a table which is travelable generally longitudinally of the work. Thus the roll has three movements, one toward and away from the work upon the arm, the second pivotally with respect to the work due to pivotal movement of the arm and the third generally longitudinally of the work due to travel of the table. It has been customary to effect each of these three movements of the roll separately by fluid pressure means, valves being provided for controlling the delivery of fluid to effect the various movements of the roll. The operation of the valves has been performed manually by an operator known as a spinner. Long training and experience are required to develop a skilled spinner and from the standpoint of manual operation of the roll controlling valves the spinning art is perhaps the most difficult of all the metal working arts. Skilled spinners are very highly paid.

Due to war conditions the demand for skilled spinners has increased while the supply has decreased. Various articles used in war are made by spinning, such, for example, as bomb casings, as mentioned above. Articles such as these are made in very large quantities and the spinning capacity of the steel industry in the United States has been multiplied in the last two or three years. Due to the lack of skilled spinners and the great amount of training required to develop them great difficulties have been encountered in operating spinning plants, efficiency has been greatly reduced and spoilage of work and damage to equipment has increased.

It has always been considered that control of the spinning roll in a spinning machine is an operation which must be performed by a highly

skilled operator and which cannot satisfactorily be performed by any control mechanism. Previous efforts have been made to control the movements of a spinning roll relatively to the work by control mechanism, but these have failed. This has been due to the inability to overcome difficulties incident to variable factors such as fluid pressure, temperature of the work, quality of the steel, etc. The skilled spinner can, almost 10 subconsciously, allow for such variables while the spinning operation is in progress and indeed it is because of the existence of such factors that such high skill is required in spinning.

I have invented spinning mechanism comprising control means for controlling the movements of the spinning roll relatively to the work whereby the spinning operation may be carried out entirely without the services of a skilled spinner and the results accomplished are superior to those 15 accomplished in manually controlled spinning because the human equation is eliminated. I have found that by my control mechanism I can control the operation of a spinning roll in its shifting movements relatively to the work despite variable factors such as fluid pressure, temperature of the work, quality of the steel, etc.

I provide, in a spinning machine in which rotating work is shaped by a spinning roll, means for shifting the position of the roll relatively to the work and a control device for controlling the shifting means so constructed and arranged as to 20 repeatedly effect a predetermined sequence of movements of the roll relatively to the work. I preferably employ a control device comprising 25 cyclically operable control means and connections between the control means and the means for shifting the spinning roll relatively to the work effecting a predetermined sequence of movements of the roll relatively to the work upon 30 each cycle of operation of the control means. I have found it desirable to employ cam means for 35 effecting control of the spinning roll and I preferably employ a series of cams each having connections for controlling one of the characteristic 40 movements of the roll as described above.

I also provide, in a spinning machine in which rotating work is shaped by a spinning roll, a control device, connections between the control device and the roll for shifting the roll relatively to the work upon operation of the control device and other connections between the roll and the control device responsive to shifting movements of the roll for modifying the operation of the first 45 mentioned connections so that movements of the roll relatively to the work are determined coop-

eratively by the control device and the position of the roll. Specifically, I prefer to employ a control device comprising cyclically operable control means for controlling the position of the roll relatively to the work. I may employ a fluid pressure valve casing, a valve movable in the casing, fluid connections between the casing and the spinning roll operable when the valve is in one position relatively to the casing to admit fluid to shift the roll relatively to the work and other connections between the roll and the casing responsive to movements of the roll for moving the casing relatively to the valve so that movements of the roll relatively to the work are determined cooperatively by the position of the valve and the position of the casing determined by the position of the roll.

Other details, objects and advantages of the invention will become apparent as the following description of a present preferred embodiment thereof proceeds.

In the accompanying drawings I have shown a present preferred embodiment of the invention, in which:

Figure 1 is a plan view of the portion of a spinning machine which includes the mechanism for controlling the operations of the spinning roll;

Figure 2 is an end elevational view of the mechanism shown in Figure 1 as viewed from the right-hand end of that figure, but to enlarged scale;

Figure 3 is a fragmentary elevational view to further enlarged scale of a portion of the control mechanism shown in Figures 1 and 2, Figure 3 being taken looking toward the right from the left-hand end of Figure 2;

Figure 4 is a fragmentary elevational view of a portion of the mechanism shown in Figures 1, 2 and 3, Figure 4 showing part of the control mechanism at the left of Figure 2 and at the extreme lower left of Figure 1 but as viewed from the right in Figure 2 and from the upper portion of the sheet in Figure 1;

Figure 5 is a vertical transverse cross-sectional view taken on the line V—V of Figure 3;

Figure 6 is a vertical transverse cross-sectional view taken on the line VI—VI of Figure 3;

Figure 7 is a vertical transverse cross-sectional view taken on the line VII—VII of Figure 3;

Figure 8 is a fragmentary elevational view to further enlarged scale of one of the fluid pressure valves as viewed from outside the valve casing;

Figure 9 is a vertical cross-sectional view taken on the line IX—IX of Figure 8 and showing the valve in the casing;

Figure 10 is a horizontal cross-sectional view taken on the line X—X of Figure 8;

Figure 11 is an enlarged face view of the cam for controlling travel of the table;

Figure 12 is an enlarged face view of the cam for controlling swinging of the arm on which the spinning roll carriage is mounted;

Figure 13 is a flow diagram showing the fluid pressure lines from the valves to the cylinders for operating the spinning roll; and

Figure 14 is a diagram showing how the spinning roll is shifted relatively to the work during spinning.

Referring now more particularly to the drawings, there is shown a spinning machine comprising rotatable work holding means designated generally by reference numeral 2 which may be of standard construction known to those skilled in the art and hence is not described or illustrated in detail. The work holding means is rotated about

a horizontal axis and holds the work to be spun so that the work projects axially from the work holding means. In the illustrated embodiment the work is initially a steel tube 3 which is held by the work holding means 2 and projects from the right-hand end of the work holding means, viewing Figures 1 and 14. The work is rotated about its own axis. The means for rotating the work holding means 2 may also be of standard construction known to those skilled in the art and hence is not described or illustrated in detail. Before the work is spun it is preheated to a bright red heat as is standard practice in the spinning art. It is rotated at high speed, which may be in the neighborhood of 1000 R. P. M.

While the work 3 is thus held and rotated by the work holding means 2 it is acted upon by a spinning roll 4 which is adapted to be shifted relatively to the work during the spinning operation so as to shape the projecting end of the work. In the illustrated embodiment the projecting end of the work 3 which is initially in tubular form is spun into substantially closed pointed form as shown in Figures 1 and 14. The specific example shown in the drawings is of the spinning of the nose end of a bomb casing. The shifting movements of the spinning roll 4 relatively to the work must be carefully controlled and the spinning roll must move back and forth over the work generally longitudinally of the work while at the same time it is advanced toward the axis of the work and also axially of the work toward the left viewing Figures 1 and 14. The movements of the spinning roll must be such as to generally shape the work into the desired ultimate form while avoiding prolonged continuous contact with any localized portion of the work, as well known in the art. As above mentioned, the spinning roll is customarily, and as shown in the illustrated embodiment, mounted on a carriage mounted for movement toward and from the work, such carriage being in turn carried by an arm, the arm being mounted on and pivotally movable relatively to a table which is travelable generally longitudinally of the work. The carriage is designated 5, the arm is designated 6 and the table is designated 7 in the drawings.

The spinning roll 4 is mounted on the carriage 5 upon a shaft 8 on which it is rotatable during the spinning operation. The roll is not separately driven but is turned by contact with the rapidly rotating heated work. The roll shaft 8 is journaled in the carriage 5, which carriage is slidable back and forth from right to left and vice versa viewing Figure 2. The carriage 5 slides in the arm 6 which has pivotal movement about a vertical axis A (see Figures 1 and 2), the arm being carried by the table 7. The table 7 travels in the transverse or right and left direction viewing Figure 1.

The sliding movement of the carriage 5 on the arm 6, the pivoting of the arm 6 upon the table 7 and the travel of the table 7 longitudinally of the work are all preferably, and as shown in the illustrated embodiment, accomplished by fluid pressure means. A fluid pressure cylinder 9 is mounted on the arm 6. A lug 10 carried by the carriage 5 projects downwardly therefrom. A piston in the cylinder 9 has its piston rod 11 connected with the lug 10 at 12. Thus when fluid is admitted behind the piston in the cylinder 9 (i. e. to the right of such piston viewing Figure 2) the carriage 5 carrying the spinning roll 4 is advanced toward the left viewing that figure. Conversely, when fluid is admitted in front of the

piston in the cylinder 9 (i. e. to the left of such piston viewing Figure 2) the carriage 5 carrying the spinning roll 4 is retracted toward the right viewing that figure.

A second fluid pressure cylinder 13 is mounted on the table 7 by a pivotal mounting 14 which allows the cylinder to turn somewhat in operation. The piston rod 15 of the piston in the cylinder 13 is pivoted at 16 to a lug 17 carried by the arm 6 and projecting generally radially of the axis A. When fluid is admitted behind the piston in the cylinder 13 (i. e. to the right of such piston viewing Figure 1) the arm 6 is swung in the counter-clockwise direction about the axis A viewing that figure. Conversely, when fluid is admitted in front of the piston in the cylinder 13 (i. e. to the left of such piston viewing Figure 1) the arm 6 is swung in the clockwise direction about the axis A viewing that figure. A third cylinder 18 is stationarily mounted relatively to the floor so that it has no movement. The piston rod 19 of the piston in the cylinder 18 is connected at 20 to the table 7, which, as above stated, is mounted for travel longitudinally or axially of the work (i. e. in the left and right direction in Figure 1). When fluid is admitted behind the piston in the cylinder 18 (i. e. to the right of such piston viewing Figure 1) the table 7 carrying the arm 6 is advanced toward the left viewing that figure. Conversely, when fluid is admitted in front of the piston in the cylinder 18 (i. e. to the left of such piston viewing Figure 1) the table 7 carrying the arm 6 is retracted toward the right viewing that figure.

The mechanism above described is standard and does not constitute my invention. It has been described because a general understanding of the operation of the spinning machine is necessary to an understanding of my invention, but the portions of the mechanism which have been described in general terms will not be more specifically described and are not shown in detail in the drawings because they are well known to those skilled in the spinning art.

Mounted on the floor generally alongside the spinning machine proper is a housing 21 carrying a support 22 having bearings 23 in which is journaled for rotation a cam shaft 24. Keyed to the cam shaft 24 to rotate therewith are three cams 25, 26 and 27. Mounted on the base 28 of the housing 21 is an electric motor 29 connected through a coupling 30 with a speed reducer 31 whose driven shaft carries a sprocket 32. The cam shaft 24 carries a sprocket 33. A sprocket chain 34 is trained about the sprockets 32 and 33. When the motor 29 is energized it drives the cam shaft 24 through the mechanism just described. The cam shaft 24 rotates relatively slowly due to the interposition of the speed reducer 31.

The respective cams 25, 26 and 27 are for controlling, through mechanism now to be described, the flow of fluid to the respective cylinders 18, 13 and 9 and, consequently, the movement of the carriage 5 relatively to the arm 6, the swinging of the arm 6 on the table 7 and the travel of the table 7 axially of the work. To this end each of the three cams 25, 26 and 27 operates a fluid pressure control valve. The casing for the valve operated by the cam 25 is designated 35, the casing for the valve operated by the cam 26 is designated 36 and the casing for the valve operated by the cam 27 is designated 37. All three of the valves and casings are of the same general construction, but the casings 35 and 36 are, as will presently

appear, mounted for movement consonant with the travel of the table 7 and the swinging of the arm 6, respectively, for a purpose which will be explained, while the casing 37 is stationarily mounted upon the housing base 28 by a bracket 38.

A casing and valve shown in detail in Figures 8, 9 and 10 may be either the casing 35 and its contained valve or the casing 36 and its contained valve, but for purposes of illustration and explanation the casing shown in Figures 8, 9 and 10 is designated as the casing 35. The casing has four fluid passages designated, respectively, 39, 40, 41 and 42. The passage 39 opens into an elongated passageway 43 as shown in Figure 9 which at its upper end communicates with the annular passage 44 and at its lower end communicates with the annular passage 45. The passage 40 opens into an annular passage 46. The passage 41 opens into an annular passage 47. The passage 42 opens into an annular passage 48. Within the casing 35 is a liner 49 having ports 50 therethrough communicating internally with the bore of the casing (i. e. the interior of the liner) and externally with the respective annular passages 46, 47 and 48.

The valve which operates within the casing 35 is designated 51. The valve is of the spool type and is adapted to be moved axially of the casing, as will be apparent from Figure 9. The valve has a stem 52 and a nose 53. The casing 35 has an extension 54 having a cavity 55 within which is disposed a compression coil spring 56 which bears against the nose of the valve 51 to urge the valve downwardly viewing Figure 9. The valve has two rings or enlargements 57 and 58 which are spaced apart longitudinally of the valve a distance on centers equal to the longitudinal distance on centers between the ports 50 leading to the annular passages 47 and 48. Each of the rings 57 and 58 has a dimension longitudinally of the valve somewhat greater than the longitudinal dimension of each of the ports 50 so that when the valve is in the neutral position as shown in Figure 9 the ring 57 closes the ports 50 communicating with the passage 47 and the ring 58 closes the ports 50 communicating with the passage 48. When the valve 51 is raised within the casing, compressing the spring 56, until the ring 57 uncovers the ports communicating with the passage 47 and the ring 58 uncovers the ports communicating with the passage 48 this will result in communication between the passages 46 and 47 and communication between the passages 45 and 48. Conversely, when the valve 51 is lowered within the casing, allowing the spring 56 to expand, until the ring 57 uncovers the ports communicating with the passage 47 and the ring 58 uncovers the ports communicating with the passage 48 this will result in communication between the passages 46 and 48 and communication between the passages 44 and 47.

The passage 40 is connected with a source of fluid pressure (not shown). This may, for example, be an oil pump maintaining a substantially constant head of oil, in which case the passage 40 is connected with the high pressure side of the oil pump. The passage 39 is connected with the low pressure side of the oil pump. The passage 41 is connected with the cylinder 18 in front of the piston therein (see Figure 13). The passage 42 is connected with the cylinder 18 behind the piston therein. When the valve 51 is in the neutral position as shown in Figure 9 oil does not flow to or from the cylinder 18 because the passages 41 and 42 which communicate with the

cylinder are closed by the respective rings 57 and 58. When the valve moves up to allow communication between the passages 46 and 47 oil flows from the high pressure side of the oil pump through the passages 40, 46, 47 and 41 and enters the cylinder 18 in front of the piston therein. At the same time the oil line from behind the piston in the cylinder 18 and which is connected with the passage 42 is through the passages 48, 45, 43 and 39 brought into communication with the low pressure side of the oil pump so that oil flows out from behind the piston and the piston moves from left to right viewing Figures 1 and 13. When the valve moves down to allow communication between the passages 46 and 48 oil flows from the high pressure side of the oil pump through the passages 40, 46, 48 and 42 and enters the cylinder 18 behind the piston therein. At the same time the oil line from in front of the piston in the cylinder 18 and which is connected with the passage 41 is through the passages 47, 44, 43 and 39 brought into communication with the low pressure side of the oil pump so that oil flows out from the front of the piston and the piston moves from right to left viewing Figures 1 and 13.

Thus movement of the piston in the cylinder 18 is controlled by the relative positions of the valve 51 and the casing 35; when the valve moves upwardly relatively to the casing from the neutral position shown in Figure 9 the piston in cylinder 18 moves toward the right viewing Figures 1 and 13 and when the valve moves downwardly relatively to the casing from the neutral position shown in Figure 9 the piston in cylinder 18 moves toward the left viewing Figures 1 and 13.

The pistons in cylinders 13 and 9 are controlled in exactly similar manner by the operation of the valves in the casings 36 and 37, respectively. Each of the valve casings has communication with the high pressure side of the oil pump, the low pressure side of the oil pump and both ends of the cylinder which it controls. Thus by appropriate control of the valve in the casing 36 the arm 6 may be swung back and forth about the axis A and by appropriate control of the valve in the casing 37 the carriage 5 may be advanced toward and retracted from the work along the arm 6. It will be noted in Figure 13 that flexible connections with the cylinders 9 and 13 which move during operation of the spinning machine are indicated at 59, such connections being shown as rubber or similar flexible hoses connected with pipes 60 leading to the valves. Similarly, since in operation of the spinning machine the valve casings 35 and 36 also move, as will presently be described, flexible connections 61 from the pipes to such valve casings are also shown.

As shown in Figures 3 and 5 the cam 25 directly underlies the valve casing 35 and the valve therein, as shown in Figures 3 and 6 the cam 26 directly underlies the valve casing 36 and the valve therein, and as shown in Figures 3 and 7 the cam 27 directly overlies the valve casing 37 and the valve therein. Each of the valves in the casings 35 and 36 is spring pressed downwardly toward the corresponding cam and the valve in the casing 37 is spring pressed upwardly toward the cam 27.

Pivoted at 62 to the stem 52 of the valve 51 in the valve casing 35 is a pair of links 63 through whose lower ends passes a pin 64. Rotatably mounted on the pin 64 intermediate the links 63 is a cam following roller 65 (see Figure 3) which at all times is pressed downwardly upon and follows the cam 25. The valve casing 35 is bolted

to a mounting 66 by bolts 67. Projecting downwardly from the mounting 66 is a bifurcated bracket 68 carrying at its lower extremity a pin 69. Links 70 are pivoted to the pins 68 and 64 as shown in Figures 3 and 5. This construction allows the roller 65 to follow the cam 25 without binding or the tendency to impart sidewise stresses to the valve stem 52. While the angularity of the links 63 changes slightly during operation of the spinning machine, such change in angularity does not deleteriously affect the operation of the valve.

The connections through which the cam 26 operates the valve in the casing 36 are exactly analogous to the connections through which the cam 25 operates the valve in the casing 35 as just explained. Pivoted at 71 to the stem 72 of the valve in the casing 37 is a pair of links 73 through whose upper ends passes a pin 74. Rotatably mounted on the pin 74 intermediate the links 73 is a cam following roller 75 (see Figure 3) which at all times is pressed upwardly against and follows the cam 27. The housing 21 carries a bracket 76 to which is pivoted at 77 a lever 78 through which the pin 74 passes as shown in Figure 7. The end of the lever forms a handle 79 which, if desired, may be operated manually to move downwardly the valve in the casing 37. As will be seen from Figure 13, bearing in mind that the structure of the casing 37 and the valve therein is to all intents and purposes the same as the structure of the casing 35 and the valve 51 therein as shown in Figures 8, 9 and 10, when the valve in the casing 37 is moved downwardly communication is established between the high pressure side of the oil pump and the front of the piston in the cylinder 9, the effect of which is to move the spinning roll 4 back away from the work. Thus the handle 79 may be used in emergencies or to supplement the automatic operation of the mechanism when necessary or desirable to move the spinning roll to inoperative position relatively to the work. Ordinarily manual operation of the spinning roll is unnecessary and the valve in the casing 37 is controlled by the cam 27 through the roller 75 and links 73. As explained above, contact between the roller 75 and the cam 27 is maintained at all times by a spring pressing upwardly against the valve in the casing 37 analogous in function to the spring 56 which presses downwardly against the valve 51 in the casing 35.

Means are provided for moving the valve casings 35 and 36 consonantly with movements of the table 7 and the arm 6, respectively, so that movements of the spinning roll 4 relatively to the work are determined cooperatively by the control means and the position of the roll. The mounting 66 carrying the valve casing 35 (Figure 5) is slidable vertically in guideways 80 in the housing 21 so that the casing 35 may move vertically up and down relatively to the housing and coaxially with the valve 51. Mounted atop the housing 21 on a stub shaft 81 is a sprocket 82. Connected with the top of the mounting 66 and extending about and meshing with the sprocket 82 as shown in Figure 5 is a sprocket chain 83. Also carried by the housing 21 is a stub shaft 84 carrying a sprocket 85. Extending about the meshing with the sprocket 85 as shown in Figure 4 is a sprocket chain 86. A link 87 connects the sprocket chains 83 and 86 as shown in Figures 4 and 5. Connected with the end of the sprocket chain 86 is a rod 88 having an adjustable connection 89 with another rod 90, the rods 88 and

90. together with the adjustable connection 89 constituting in effect a link of adjustable length. Such link is pivoted at 91 to a short link 92 which in turn is pivoted at 93 to a transverse link 94 swingable about a vertical pivot pin 95 in a stationary base 96. The opposite end of the link 94 is pivoted at 97 to a link 98, which in turn is pivoted at 99 to the table 7.

Connected with the top of the extension 54 of the casing 35 is a rod 100 which enters a cylinder 101 mounted atop the housing 21. The rod 100 carries a piston 102 fitting within the cylinder 101. Air under pressure is during operation of the spinning machine continuously admitted to the top of the cylinder 101 behind the piston 102 through a pipe 103. Thus the casing 35 is at all times urged downwardly viewing Figure 5 and the sprocket chains 83 and 85 and the links 88-90 and 92 are maintained in fully extended position as shown in Figure 1. The sprocket chains and links act only in tension and not in compression.

When the cam 25 turns in the clockwise direction viewing Figure 5 as indicated by the arrow in that figure and the roller 65 passes from the high portion of the cam as shown in Figure 5 to a lower portion thereof the valve 51 moves downwardly in the casing 35, resulting in the admission of oil under pressure behind the piston in the cylinder 18 and, consequently, advancement of the table 7 from right to left viewing Figure 1. The extent of downward movement of the valve 51 is determined by the cam 25. As the table 7 moves toward the left viewing Figure 1 it causes the link 94 to swing about the pivot 95 in the counter-clockwise direction viewing Figure 1 since the pivot is stationary and the table moves. This allows movement generally toward the left viewing Figure 1 of the links 88-90 and 91 and consequent downward movement under the action of the air behind the piston 102 of the valve casing 35. The result is that after a given downward movement of the valve 51 in the casing 35 which causes a movement of the table 7 toward the left viewing Figure 1, and while the roller 65 is riding on a circular portion of the cam 25 the casing 35 moves downwardly and in effect catches up with the valve 51, thus bringing the valve into neutral position relatively to the casing as shown in Figure 9 and interrupting the flow of fluid to and from the cylinder 18. The result is that the piston in the cylinder 18 and the table 7 connected therewith are maintained temporarily in a new or advanced position relatively to the position they occupied prior to downward movement of the valve followed by downward movement of the casing. Then when the roller 65 descends onto a still lower portion of the cam 25 the valve 51 moves downwardly still farther, resulting in an additional movement of the table 7 toward the left viewing Figure 1, and that movement in turn causes downward movement of the casing 35 as above explained. In this way through proper design of the cam 25 the table 7 can be and is caused to move step by step from right to left viewing Figure 1 as the spinning progresses. At the end of the spinning operation the roller 65 rides up from the lowest portion of the cam 25 onto the highest portion thereof and the table 7 returns in a continuous movement toward the right to its initial position. This control mechanism effects the desired control of movement of the table 7 despite fluctuations in the pressure of the oil and other variable factors. Due to the connections between the table and

the valve casing which causes the valve casing to in effect follow up the valve step by step during the spinning operation the table can be positively advanced in any desired number of steps and maintained in predetermined positions for desired periods of time dependent upon the design of the cam 25.

The swinging movement of the arm 6 is controlled by the cam 26 precisely analogously to the control of the travel of the table 7 as just explained. The mounting 104 carrying the valve casing 36 (Figure 6) is slidable vertically in guideways 105 in the housing 21 so that the casing 36 may move vertically up and down relatively to the housing and coaxially with the valve in that casing. Mounted atop the housing 21 on a stub shaft 106 is a sprocket 107. Connected with the top of the mounting 104 and extending about and meshing with the sprocket 107 as shown in Figure 6 is a sprocket chain 108. Also carried by the housing 21 is a stub shaft 109 carrying a sprocket 110. Extending about and meshing with the sprocket 110 as shown in Figure 4 is a sprocket chain 111. An adjustable link 112 connects the sprocket chains 108 and 111 as shown in Figures 4 and 6. The structure of the adjustable link 112 is similar to that of the adjustable link 88-90 shown in Figure 1 and its structure is clearly shown in Figure 6. The sprocket chain 111 is connected at 113 (Figure 4) with another sprocket chain 114 which meshes with a sprocket 115 and also has its end fastened to the sprocket 115 at 116 (see Figures 1 and 3). The sprocket 115 lies in a horizontal plane and is mounted on a stub shaft 117 carried by a bracket 118 projecting outwardly from the housing 21 as shown in Figure 1. Fast to the sprocket 115 so as always to turn therewith and projecting outwardly radially of the shaft 117 is an arm 115a pivoted at 119 to a link 120. The link 120 is pivoted at 121 to an arm 122 of a bell crank lever 123 pivotally carried by a pin 124 (Figure 2) mounted in the stationary base 96 and coaxial with the vertical pivot pin 95. The bell crank lever 123 has another arm 125 to which is pivoted at 126 a link 127 whose opposite end is pivoted at 128 to a lug 129 carried by the arm 6.

50. The valve casing 36 is normally urged downwardly (Figure 6) by means 130 exactly analogous to the corresponding means for urging downwardly the valve casing 35 (Figure 5) as described in detail above. Thus the roller 131 (Figure 3), which cooperates with the cam 26 analogously to the manner in which the roller 65 cooperates with the cam 25, is at all times maintained in contact with that cam, and the linkage just described for connecting the valve casing 36 with the arm 6 is maintained in tension.

55. When the cam 26 turns in the clockwise direction as indicated by the arrow in Figure 6 the valve in the casing 36 will be caused to move alternately up and down as will be apparent upon consideration of the contour of the cam 26 (see Figure 12). This will result in back and forth swinging movements of the arm 6. The linkage just described for connecting the valve casing 36 with the arm 6 causes the valve casing to follow up the movements of the valve caused by the cam 26 so that the back and forth swinging movement of the arm 6 may be accurately and predeterminedly controlled despite fluctuations in oil pressure and other variables which

otherwise might be difficult or impossible to compensate for.

As above mentioned, the valve casing 37 within which operates the valve controlled by the cam 27 is not movable as are the valve casings 35 and 36 but is stationarily mounted. The function of the valve which operates in the valve casing 37 is simply to move the carriage 5 carrying the spinning roll 4 along the arm 6 toward and from the work. When a high part of the cam 27 is in engagement with the roller 75 the valve in the casing 37 is in its lowermost position and the piston in the cylinder 9 is retracted to move the spinning roll away from the work. When the roller 75 contacts a low portion of the cam 27 the valve in the casing 37 moves upwardly, fluid under pressure is admitted behind the piston in the cylinder 9 and the spinning roll 4 is advanced into contact with the work. As will be seen from the design of the cam 27, during the greater portion of the cycle of that cam the spinning roll is pressed toward the work. Indeed, during the entire operative portion of the cycle that is the case, the roll being withdrawn from engagement with the work at the end of the spinning operation on a particular workpiece.

As has been explained, the three cams 25, 26 and 27 are all mounted on the cam shaft 24 so that they rotate together. During the spinning operation they simultaneously control the movement of the carriage 5 toward the work, the swinging movements of the arm 6 and the travel of the table 7. The spinning roll thus partakes of a composite movement as it at times is simultaneously moving radially toward the work, swinging about the axis A and traveling axially of the work. The precise movements of the roll will be determined by the contours of the cams 25, 26 and 27. It is to be understood that the cams may be designed to meet any particular situation and to bring about any desired movements of the roll which may be desired in spinning a workpiece into a particular finished form.

Figure 14 shows diagrammatically how the spinning roll 4 is moved during the spinning operation. The workpiece 3 is originally of full tubular form as indicated in full lines in Figure 14. The spinning roll 4 is initially moved toward the workpiece from the full line position designated *a* along the line X to the dotted line position *b*, deforming the end of the blank into generally frusto-conical shape as indicated by the dotted line Y. The roll then commences to partake of back and forth swinging movements brought about by swinging of the arm 6 about the axis A (Figure 1) and it successively assumes the positions indicated at *c* and *d* in Figure 14. During the swinging movements the table 7 travels toward the left. The result is the reshaping of the end of a workpiece to the contour indicated by the dotted line Z in Figure 14 and also shown in full lines in Figure 1.

Turning of the cam shaft 24 is, as mentioned above, effected by operation of the electric motor 29. The motor is preferably started by the manual closing of a switch after a new preheated workpiece has been set in place and clamped in the rotatable work holding means 2. The motor may be stopped manually or by a limit switch associated in any convenient manner with the mechanism so as to open the motor circuit at the end of the predetermined cycle of movements of the spinning roll. A limit switch 132 (Figures 3, 6 and 12) may be mounted adjacent the cam 25 and may be operated by a lug 133 fastened to

the cam by bolts 134 passing through an arcuate slot 135. The lug may be adjustably positioned as desired on the cam. As mentioned above, the circuit may be closed manually and it may be opened at the end of a revolution of the cam shaft 24 by operation of the limit switch 132 by the lug 133.

While I have shown and described a present preferred embodiment of the invention it is to be distinctly understood that the invention is not limited thereto but may be otherwise variously embodied within the scope of the following claims.

I claim:

1. In a spinning machine in which rotating work is shaped by a spinning roll, means for shifting the roll relatively to the work, a fluid pressure valve casing, a valve movable in the casing, means mounting the casing for movement relatively to the valve, fluid connections between the casing and said shifting means operable when the valve is in one position relatively to the casing to admit fluid to shift the roll relatively to the work and other connections between the roll and the casing responsive to movements of the roll for moving the casing relatively to the valve so that movements of the roll relatively to the work are determined cooperatively by the position of the valve and the position of the casing determined by the position of the roll.

2. In a spinning machine in which rotating work is shaped by a spinning roll, means for shifting the roll relatively to the work, a fluid pressure valve casing, a valve movable in the casing, means mounting the casing for movement relatively to the valve, control means for moving the valve, fluid connections between the casing and said shifting means operable when the valve is in one position relatively to the casing to admit fluid to shift the roll relatively to the work and other connections between the roll and the casing responsive to movements of the roll for moving the casing relatively to the valve so that movements of the roll relatively to the work are determined cooperatively by the control means and the position of the roll.

3. In a spinning machine in which rotating work is shaped by a spinning roll, means for shifting the roll relatively to the work, a control device comprising a fluid pressure valve casing, a valve movable in the casing, means mounting the casing for movement relatively to the valve, cyclically operable control means for moving the valve, fluid connections between the casing and said shifting means operable when the valve is in one position relatively to the casing to admit fluid to shift the roll relatively to the work and other connections between the roll and the casing responsive to movements of the roll for moving the casing relatively to the valve, the control device effecting a predetermined sequence of movements of the roll relatively to the work upon each cycle of operation of the control means.

4. In a spinning machine in which rotating work is shaped by a spinning roll, means for shifting the roll relatively to the work, a control device comprising a fluid pressure valve casing, a valve movable in the casing, means mounting the casing for movement relatively to the valve, rotatable cam means for moving the valve, fluid connections between the casing and said shifting means operable when the valve is in one position relatively to the casing to admit fluid to shift the roll relatively to the work and other connections

between the roll and the casing responsive to movements of the roll for moving the casing relatively to the valve, the control device effecting a predetermined sequence of movements of the roll relatively to the work upon each rotation of the cam means.

5. In a spinning machine in which rotating work is shaped by a spinning roll, means for shifting the roll relatively to the work, a control device comprising a plurality of fluid pressure valve casings, a valve movable in each casing, means mounting the casing for movement relatively to the valve, means for moving each valve, fluid connections between each casing and said shifting means operable when the corresponding valve is in one position relatively to the casing to admit fluid to shift the roll relatively to the work and other connections between the roll and at least one casing responsive to movements of the roll for moving that casing relatively to the corresponding valve, the control device effecting a predetermined sequence of movements of the roll relatively to the work upon operation of the control means.

6. In a spinning machine in which rotating work is shaped by a spinning roll, means for shifting the roll relatively to the work, a control device comprising a plurality of fluid pressure valve casings, a valve movable in each casing, means mounting the casing for movement relatively to the valve, a cam shaft, a plurality of cams on said shaft, connections between each cam and one of the valves for moving the latter upon rotation of the shaft, fluid connections between each casing and said shifting means operable when the corresponding valve is in one position relatively to the casing to admit fluid to shift the roll relatively to the work and other connections between the roll and at least one casing responsive to movements of the roll for moving that casing relatively to the corresponding valve.

7. In a spinning machine in which rotating work is shaped by a spinning roll, means for shifting the roll relatively to the work, a fluid pressure valve casing, a valve movable in the casing, means mounting the casing for movement relatively to the valve, fluid connections between the casing and said shifting means operable upon movement of the valve relatively to the casing in one direction to deliver fluid to move the roll in a corresponding direction and other connections between the roll and the casing responsive to movements of the roll in said corresponding direction to move the casing in the same direction as the direction of said movement of the valve to terminate said delivery of fluid.

8. In a spinning machine in which rotating work is shaped by a spinning roll, means for shifting the roll relatively to the work, a fluid pressure valve casing, a valve movable in the casing, means mounting the casing for movement relatively to the valve, fluid connections between the casing and said shifting means operable upon movement of the valve relatively to the casing in one direction to deliver fluid to move the roll in one direction and upon movement of the valve relatively to the casing in the opposite direction to deliver fluid to move the roll in the opposite direction and other connections between the roll and the casing responsive to movements of the roll to move the casing in the same direction as the direction of movement of the valve causing each movement of the roll to terminate delivery of fluid to move the roll.

9. In a spinning machine in which rotating work is shaped by a spinning roll, means for shifting the roll relatively to the work, a fluid pressure valve casing, a valve movable in the casing, means mounting the casing for movement relatively to the valve, and control means comprising cyclically operable means for moving the valve back and forth relatively to the casing, fluid connections between the casing and said shifting means operable upon movement of the valve relatively to the casing in one direction to deliver fluid to move the roll in one direction and upon movement of the valve relatively to the casing in the opposite direction to deliver fluid to move the roll in the opposite direction and other connections between the roll and the casing responsive to movements of the roll to move the casing in the same direction as the direction of movement of the valve causing each movement of the roll to terminate delivery of fluid to move the roll, the control means effecting a predetermined sequence of movements of the roll relatively to the work upon each cycle of operation of the valve moving means.

10. In a spinning machine in which a rotating tube is shaped by a spinning roll, a control device, connections between the control device and the roll for shifting the roll relatively to the tube upon operation of the control device and other connections between the roll and the control device responsive to shifting movements of the roll for modifying the operation of the first mentioned connections so that movements of the roll relatively to the tube are determined cooperatively by the control device and the position of the roll.
